US00D852217S

(12) **United States Design Patent** (10) Patent No.: **US D852,217 S**
Li et al. (45) Date of Patent: **** Jun. 25, 2019**

(54) **MOBILE COMMUNICATION TERMINAL
WITH GRAPHICAL USER INTERFACE**

(71) Applicant: **BELJING KINGSOFT INTERNET
SECURITY SOFTWARE CO., LTD.,**
Beijing (CN)

(72) Inventors: **Yuan Li**, Beijing (CN); **Delin Liu**,
Beijing (CN); **Zhe Ma**, Beijing (CN)

(73) Assignee: **Beijing Kingsoft Internet Security
Software Co., Ltd.**, Beijing (CN)

(**) Term: **15 Years**

(21) Appl. No.: **29/635,321**

(22) Filed: **Jan. 30, 2018**

(57) **CLAIM**

The ornamental design for a mobile communication terminal with graphical user interface, as shown and described.

DESCRIPTION

FIG. 1 is a front elevation view of a first embodiment of a mobile communication terminal with graphical user interface showing our new design; and,

FIG. 2 is a front elevation view of a second embodiment of the mobile communication terminal with graphical user interface.

The broken lines shown in the drawings of a mobile communication terminal and certain graphic features of the graphical user interface form no part of the claimed design.

1 Claim, 2 Drawing Sheets
